UNITED STATES PATENT OFFICE.

ZENO W. WICKS, OF FORT WORTH, TEXAS, ASSIGNOR TO WORTHINGTON PUMP AND MACHINERY CORPORATION, OF NEW YORK, N. Y., A CORPORATION OF VIRGINIA.

COMPRESSOR OR PUMP.

Application filed April 3, 1925. Serial No. 20,335.

To all whom it may concern:

Be it known that I, ZENO W. WICKS, a citizen of the United States, residing at Fort Worth, county of Tarrant, and State of Texas, have invented certain new and useful Improvements in Compressors or Pumps, fully described and represented in the following specification and the accompanying drawings, forming a part of the same.

The present invention relates to improvements in compressors or pumps.

It is the object of the invention to provide an improved plunger construction which will be found especially important as applied to plungers of the higher stage cylinders of air and gas compressors. By the use of the present arrangement side pressure on the stuffing box packing and stresses tending to cause binding of the plunger head in the cylinder bore, are avoided in case of misalignment of the plunger, which may be due to wear or other causes, while efficient cooling of the plunger head and the plunger rod throughout its length is secured. The improvement thus provides an arrangement by which straight metallic packing, as well, of course, as other types of packing, may be used with advantage in the stuffing box, and by which liquid cooling of the stuffing box and oil supply therein for lubricating the plunger usually may be dispensed with, and thus avoid danger of contaminating the air or gas being compressed.

In the accompanying drawings forming a part of this specification, there is shown in central section and partial elevation a compressor cylinder and a plunger and driving connection therefor embodying the invention in a preferred form, and this construction will now be described in detail in connection with said drawings, and the novel features of the invention then be specifically pointed out in the claims.

Referring to the drawings, 11 indicates a compressor cylinder provided with the usual liner 12, suction and discharge valves 13, 14, respectively, communicating with the cylinder clearance, and a stuffing box 15. Plunger rod 1 preferably and as shown has formed integrally therewith a plunger head 2 arranged to work within the liner 12, although it will be understood that the plunger head 2 may be formed separately from and secured to the rod 1 in any desired

manner. According to the arrangement shown, the outer end of the rod 1 is connected to driving yoke 3, the inner side of the latter being arranged to abut against a flange 4 formed on such rod, and the end of the rod passing through the yoke and threaded to receive a nut or nuts 5, two of the latter being shown in the present instance in order to secure locking engagement thereof. Secured to the plunger head 65 2, as by threaded engagement therewith as shown or otherwise, is a tubular member 6, preferably formed of seamless steel and the exterior surface of which preferably is highly polished to secure a smooth running fit 70 with the stuffing box packing. The member 6 at its outer end is not rigidly connected to the rod 1, but an annular space is provided between these parts at such point, so as to permit of transverse movement of the 75 plunger rod 1 with respect to the tube 6, as hereafter explained. The end of the tube 6 is, however, shown as closed by a hood 7 of rubber or other flexible material, which may be secured in place and in fluid tight 80 engagement with the tube 6 and flange 4 by metal bands under which the hood material is clamped, which are held in place by screws taking into the flange 4 and tube 6. 85

It will be obvious from the construction so far described that the tubular member 6, on the effective strokes of the plunger 1, will be pulled through the stuffing box rather than pushed therethrough, thus securing 90 easier functioning of these running parts, while the provision for transverse movement of the outer end of the plunger 1 with respect to the tube 6, efficiently provides for self-alinement of the member 6 with respect 95 to the cylinder bore should the plunger 1, for any reason, be thrown out of alinement. Side pressure on the stuffing box packing by the plunger rod is therefore avoided, so that straight metallic packing may be used with 100 advantage. While the self-alining feature above referred to will efficiently function to compensate for inaccuracies in alinement resulting from wear of the parts or other causes, plunger rod 1 preferably will be so 105 proportioned with respect to its length and the total load to be carried by the head 2, that the rod will possess a limited degree of flexibility. Thus, on slight misalignment the peripheral running surface on plunger head 110

- 2 will remain parallel with the cylinder bore without being subjected to any such stresses as might tend to cause excessive friction and wear of these parts. With the construction so far described, it will be obvious that a chamber 8 of ample size is provided between the plunger rod 1 and the inner wall of the tubular member 6. According to the arrangement shown, cooling fluid is maintained in this chamber and constantly circulated therethrough, such fluid preferably and as shown being admitted thereto by providing a flexible pipe *a* attached to the outer end of the plunger rod 1 and arranged to communicate with a central bore 9 extending the full length of such rod and well into the head 2 thereon, the cooling fluid entering the chamber 8 by way of passages 10. The plunger rod and head are thus first cooled by the entering fluid and the maximum effect of such cooling fluid on the head 2 thus obtained, while the rod 1 and tubular member 6 are effectively cooled throughout their length. The fluid in chamber 8 passes off through a flexible tube *b* leading to any desired point. While the stuffing box construction shown includes a lantern ring and passages communicating with the chamber therein thus formed so that cooling fluid or lubricant may be circulated therein, it will be found that with the present arrangement above described this cooling or lubricating means may be dispensed with in most cases, as efficient lubrication of the plunger as at present constructed may in most cases be secured simply by applying a few drops of oil to the plunger rod at a point outside the stuffing box when the plunger rod is at the limit of its outstroke.
- 40 While the invention has been described in connection with a compressor cylinder and its plunger and driving connection therefor, it is obvious that the arrangement herein shown and described is applicable with advantage to apparatus other than air or gas compressors in which cooling of the plunger with provision for self-alinement thereof are important, and it will be understood, furthermore, that various changes in the form and arrangement of the parts shown and described may be made while still retaining the invention defined by the claims.
- 55 What is claimed is:
- 55 1. A compressor or pump plunger, comprising, in combination, a plunger head, a tubular member secured to said head, a flexible plunger rod within said tubular member arranged to drive said head, and means for
- circulating cooling fluid through said rod 60 and head.
2. A compressor or pump plunger, comprising, in combination, a plunger head, a tubular member secured to said head, a flexible plunger rod within said tubular member 65 arranged to drive said head, and means for circulating cooling fluid through said plunger head and the chamber between the plunger rod and tubular member.
3. A compressor or pump plunger, comprising, in combination, a plunger head, a tubular member secured to said head, a flexible plunger rod within said tubular member arranged to drive said head, a passage in 70 said plunger rod connecting with the chamber between the rod and tubular member, and means for continuously circulating cooling fluid through the plunger rod and chamber.
4. A compressor or pump plunger, comprising, in combination, a plunger head, a tubular member secured to said head and arranged to have a running fit with the cylinder bore, a plunger rod within said tubular member 75 arranged to drive said head, a passage in the plunger rod extending into the plunger head and communicating with the chamber between the tubular member and said plunger rod, and means for circulating cooling fluid through said passage and chamber.
- 40 5. A compressor or pump plunger, comprising, in combination, a plunger head, a tubular member secured to said head, a plunger rod within said tubular member arranged to drive said head, passages in the 80 plunger rod communicating with the plunger head and the chamber between said tubular member and the plunger rod, and flexible connections for circulating cooling fluid through said passages and chamber.
- 45 6. A compressor or pump plunger, comprising, in combination, a plunger head, a tubular member secured to said head and arranged to have a running fit with the cylinder bore, a plunger rod within said tubular member 85 arranged to drive said head, passages in the plunger rod arranged to supply cooling fluid to said head and the chamber between said tubular member and plunger rod, and flexible connections arranged to deliver cooling fluid to the plunger rod passages and carry off the fluid from 90 said chamber.
- 50 In testimony whereof, I have hereunto 95 set my hand.
- ZENO W. WICKS.
